DESIGN FOR A DECORATIVE WINDMILL

Ralph H. Niece, Evanston, Ill.

Application November 20, 1936, Serial No. 66,049

Term of patent 7 years

To all whom it may concern:

Be it known that I, Ralph H. Niece, a citizen of the United States, residing at Evanston, in the county of Cook and State of Illinois, have invented a new, original, and ornamental Design for a Decorative Windmill, of which the following is a specification, reference being had to the accompanying drawing, forming a part thereof.

Referring to the drawing:

Fig. 1 is a front elevational view of a decorative windmill embodying my new design;

Fig. 2 is a rear elevational view of a decorative windmill embodying my new design; and

Fig. 3 is a side elevational view of a decorative windmill embodying my new design, said view being taken from the left of Fig. 1.

I claim:

The ornamental design for a decorative windmill, as shown.

RALPH H. NIECE.
